(57) **CLAIM**

The ornamental design for part for a feeding bottle, as shown and described.

DESCRIPTION

FIG. 1 is a part of a teat unit of a feeding bottle in a perspective view;

FIG. 2 is a side view thereof;

FIG. 3 is a different side view thereof;

FIG. 4 is a different side view thereof;

FIG. 5 is a different side view thereof;

FIG. 6 is a top view thereof; and,

FIG. 7 is a bottom view thereof.

The broken lines illustrate portions of the drawings that form no part of the claimed design.
